[57] CLAIM

The ornamental design for a game board, as shown and described.

DESCRIPTION

FIG. 1 is a front elevational view of a game board showing my new design;

FIG. 2 is a side elevational view, the opposite side being a mirror image;

FIG. 3 is a bottom plan view;

FIG. 4 is a top plan view;

FIG. 5 is a rear elevational view;

FIG. 6 is a perspective view with the game board in a partially extended position; and

FIG. 7 is an exploded perspective view with the game board in a fully extended position with the storage cover removed and playing pieces exposed.
